UNITED STATES PATENT OFFICE.

NIKOLAI HILL, OF MELLEN, WISCONSIN.

RAILWAY TIE.

Application filed March 24, 1928. Serial No. 264,365.

This invention relates to new and useful improvements in railway devices, and particularly to railway ties.

One object of the invention is to provide a railway tie which is equipped with novel and efficient means for supporting and attaching railway rails thereto.

Another object is to provide a railway tie formed from separable and identically constructed sections, each of the sections being provided with a rail chair.

Another object is to provide a railway tie of this character wherein novel cushioning means are located beneath each of the rail chairs, whereby to absorb the jars and shocks incident to the passage of trains thereover.

Other objects and advantages will be apparent from the following description when taken in connection with the accompanying drawing.

In the drawing:

Figure 1 is a side elevation of a railway tie made in accordance with the present invention.

Figure 2 is a top plan view of the same.

Figure 3 is a transverse sectional view on the line 3—3 of Figure 2.

Figure 4 is a perspective view of one of the sections of the tie.

Referring particularly to the accompanying drawing, it will be seen that the tie is composed of two identically constructed and formed sections A and B, so that a detailed description of one section will suffice.

The sections each comprise a vertical web portion 10 and a base flange portion 11. As clearly seen in the perspective view, Figure 4, the base portion is cut away at one side of the tie, as shown at 12, while the said portion is cut away, as at 13, at the other side of the tie, the cut at 12 being considerably deeper than that of the cut at 13, whereby the flange or base is of different lengths at the opposite sides of the tie. Each web, which

is disposed against the other web, is extended to a considerable distance beyond the cut 13, and is somewhat reduced in height, as indicated at 14, and in the upper edge of this extended portion of the web there is formed a transverse recess 15, which cooperates with a corresponding recess in the other section, when said sections are properly connected together, as seen in Figures 1 and 2 of the drawing, to receive the cushion member 16,

to which reference will be made later herein. 55
Mounted on the outer vertical face of the extended portion of the web 10, and having its upper face lying in the plane of the bottom wall of the recess 15, is a shelf member 17, on which is adapted to rest an end 60 portion of the said cushion member 16. In the upper edge of the other end of the web 10 there is formed a similar transverse recess 18, which registers with a corresponding recess in the other tie section, to form 65 a seat for a similar cushion member 19, seen in Figures 1 and 2, of the drawing. On the upper edge of the web 10, directly over the recess 18, is a plate 20, which forms a chair for the rail 21, suitable clamps 22 being secured to the said plate, by means of the bolts 23, for holding the rail in proper position thereon. One end of one chair rests on the cushion 16, while the corresponding end of the other chair rests on the cushion 19. Bolts 70 24 are disposed through the webs of the two sections of the tie to properly hold them together.

The before-mentioned cushions 16 and 19 may be solid blocks of wood, leather, or similar yieldable material, or there may be strong springs of any desired character placed between the block, and a metal plate 25, disposed below said block. 80

What is claimed is:

A railway tie divided vertically and longitudinally into identically shaped and constructed sections, each of the sections comprising a web portion, a base portion, and a chair seat portion, one end of the web portion extending beyond one end of the base portion and being reduced in height, said extending portion of the web having a transverse recess in the upper edge thereof, the other end of the upper edge of said web portion having a transverse recess registering with the first recess when the sections are secured together, a shelf beneath each of the first-named recesses, one end of the chair resting over a recess, and a cushion member disposed transversely in said recesses and resting on the said shelf members, said cushion members being disposed in supporting relation to corresponding ends of said chairs. 100

In testimony whereof, I affix my signature.

NIKOLAI HILL.
